WEFT FEEDING MECHANISM

Louis J. Zerbee, Bellefontaine, Ohio

Application March 24, 1947, Serial No. 736,807

19 Claims. (Cl. 139—127)

1

This invention relates to a loom and more particularly to the mechanism associated with the feeding of the weft.

In the manufacture of woven materials, such as heavy wire screen, difficulty has been encountered in manipulating the weft. In my Patent No. 2,272,456 patented February 10, 1942, for Loom, a weft feeding mechanism has been shown, wherein the weft wire is crimped. This invention is an improvement upon my loom disclosed in the aforementioned patent.

An object of this invention is to crimp and simultaneously to push the crimped wire into position, the leading end of the crimped wire being guided while traversing the shed formed by the warp.

Another object of this invention is to provide a weft manipulating mechanism that is driven by the movement of the beater frame, to thereby obtain proper synchronism.

Other objects and advantages reside in the construction of parts, the combination thereof and the mode of operation, as will become more apparent from the following description.

Referring to the drawings, Figure 1 is a front elevational view of the weft manipulating mechanism mounted upon a beater frame shown only in part.

Figure 2 is a top plan view of the device disclosed in Figure 1, with parts shown in section, taken substantially on the line 2—2 of Figure 4.

Figure 3 is an enlarged fragmentary view of the weft threading mechanism.

Figure 4 is a side elevational view as seen from the right of Figures 1 and 2.

Figure 5 is another side elevational view as viewed from the left of Figures 1 and 2.

Figure 6 is an enlarged top plan view of the wire crimping mechanism, with parts broken away for the sake of clearness.

In the drawings, the reference characters 10 and 12 indicate the side frame members of a loom. The beater is mounted upon a pair of channel iron frame members 14 and 16, mounted for oscillation about the pivots 20, only one of which has been shown. The channel members 14 and 16 are several feet in height, so that the beater is mounted for oscillatory movement. The beater is oscillated about the pivots 20 by arms 28, having one end of each pivoted at 28 to the frame members 14 and 16 and the other end of each pivotally attached to the crank arms 24 keyed to a rotary shaft 22.

The beater frame includes a pair of angle irons 30 and 32, one located below the warp and one

2

located above the warp. For the sake of clearness, the reeds have not been shown on the beater, in that the reeds do not form a part of the invention and furthermore, the position of the reeds is well known to those skilled in the art.

As may best be seen by referring to the left hand side of Figures 1 and 2, the weft wire 50 is fed from a suitable source of supply through a tubular member 52, shown in cross section in Figure 6, supported upon a suitable bracket 54 attached to an upper plate 56 and a lower plate 58 supported upon the angle iron 32 and reinforced by an angle bar 60, as best seen in Figure 5. The two plates 56 and 58 are held in fixed spaced relation by a plurality of spacer members 62 having apertures for receiving bolts 64.

The wire is fed between a pair of toothed wheels 70 and 72. The toothed wheel 70 is journaled in a pair of bearings 74 and 76 mounted for adjustable movement in suitable slots in the plate members 56 and 58. These bearings are adjusted by suitable screws 80 and 82 respectively, so as to adjust the relative position of the toothed wheel 70 with respect to the toothed wheel 72.

As the wire 50 is fed between the two wheels 70 and 72, it is crimped, as clearly shown in Figures 1 and 6. The toothed wheel 72 is rotatably mounted upon the shaft 90, journaled in the plates 56 and 58 and in the bearing 92 attached to a supporting plate 94 welded to the plate 58 and reinforced by the angle iron 96 attached to the plate 58 and to the plate 94. The shaft 90 supports a rocker arm 100 provided with a pawl 102 engaging the ratchet teeth 104 on the wheel 72.

The rocker arm 100 is keyed to the shaft 90 so that as the shaft 90 is rotated or actuated in a counterclockwise direction, as viewed in Figure 6, the pawl 102 rotates the wheel 72.

The lower end of the shaft 90 has fixedly attached thereto a bevelled gear 110 meshing with a gear 112 secured to the shaft 114 journaled in bearings 116 and 118. The shaft 114 has fixedly attached thereto a gear or pinion 120 and a cam sector 122. The cam sector, as may best be seen by referring to Figures 1 and 6, has a flattened surface 124 that slides upon the cam surface 126 fixedly attached to the frame member 12 through a frame structure including the brace 128 and the frame member 130. When the beater oscillates, the gear 120 and the cam sector 122 also oscillate about the pivot 20, so as to cause the gear 120 to mesh with the gear teeth 140 on the rack 142 mounted upon the frame.

When the gear or pinion 120 meshes with the

teeth 140 on the rack 142, it can readily be seen that the shaft 114 is rotated so as to rotate the shaft 90, thereby oscillating the arm 100 carrying the pawl 102, first in a clockwise direction, as viewed in Figure 6. When the beater reverses its direction of movement, the pinion 120 reverses its direction of rotation, thereby causing the arm 100 to rotate in a counterclockwise direction, as viewed in Figure 6, at which time the pawl 102 engages the ratchet teeth 104 upon the toothed wheel 72, so as to feed the wire 50 through the crimping wheels 70 and 72 to crimp the wire, as clearly shown in Figure 6.

In order to prevent overthrow of the wheels 70 and 72, a spring-urged toothed member 150, best seen in Figure 6, pivoted at 152, is spring-urged against the teeth on member 72 by means of a tension spring 154, so as to tend to arrest the movement of the wheel 72. Any other suitable brake or stop mechanism may be used. The correct length of wire is fed out by the rocker arm through the weft wire feeding device.

Due to the fact that the wire 50 has a certain degree of resiliency, it can readily be seen that in advancing across the shed, the end of the wire 50 would droop or sag, so as to engage the lower warp wires. In order to overcome this difficulty, the end of the wire 50 is guided across the shed by a wire guiding mechanism, which will now be described.

On the right hand side of the loom, as best seen in Figures 1 and 2, there is shown a tubular needle-like member 160 mounted for reciprocatory movement across the shed when it is open. This needle-like member 160 is secured to a toothed rack 162 that reciprocates across the shed when the shed is open. This rack 162 is provided with a pair of grooves 164 and 166, one above and one below the rack bar 168. A pair of guiding members 170 and 172 are positioned in the grooves 164 and 166, so as to form guides for the rack bar 168. The guide members 170 and 172 are fixedly attached upon a pair of rails 180 and 182 that are in turn attached to the angle irons 30 and 32. The guides 170 and 172 cause the rack bar 168 to travel in a straight path, so as to feed the needle-like member 160 across the shed from one side to the other and back again when the shed is open by a driving mechanism, which will now be described.

The rack bar 168 is driven by a gear 190 keyed to a shaft 192 journalled in bearings 194 and 196 secured to a plate 198 fixedly attached to a plate 200 attached by T-bars 202 and 204 secured to the angle bars 32 and 30 respectively. The lower end of the shaft 192 has keyed thereto a bevelled gear 210 meshing with a bevelled gear 212, as best seen in Figure 1. The bevelled gear 212 is keyed to a shaft 214, having mounted thereon a pinion 216 and a cam 218, similar to the pinions 120 and 122 secured to the shaft 114. The cam 218 contacts a cam surface 220 and the pinion 216 is aligned with the rack 222 fixedly secured to the frame of the loom. It can readily be seen that when the frame 14 of the beater swings from the full line position to the dotted position shown in Figure 4, the needle-like member 160 is projected from the position shown in Figure 1 into the position shown in Figure 2. While in this position the wire 50 that has already been crimped and extending through the conduit 224 is projected into the aperture in the hollow needle-like member 160, which needle-like member leads or guides the end of the weft wire across the shed.

When the beater begins to swing from the

dotted position shown in Figure 4 towards the full line position, the wire-crimping and feeding device feeds the wire across the shed formed by the warp wires 230. The gear ratio has been so selected that the wire feeds across the shed at a higher velocity than the retraction of the needle-like member 160, so that as the weft wire passes through the shed, the end of the wire advances slowly into the needle-like member 160. However, when the weft wire feeding and crimping device comes to a stop, the needle-like member 160 has not come to the end of its retractive stroke. Thus, the needle-like member 160, upon being retracted, clears the weft wire before it reaches the home position shown in Figure 1. The stop 232, carried by the cross bar 234, spanning the distance between the rails 180 and 182, functions as a stop for the rack bar 168. The stop 232 may include a rubber pad, not shown, to cushion the shock.

After the weft wire has been fed into position, it is severed by the shears 236 that move up into severing position by a mechanism not shown in this application, but fully shown and described in the above referred to patent.

In spite of the fact that the toothed wheel, or crimping wheel 72, is arrested in its movement, and the ends of the weft wires shown to the right of the screen or woven wire mesh cloth should all be equal in length, due to the overthrow or coasting effect, the ends are somewhat irregular in length. A suitable cutter 240, attached to the rotor shaft 242 of the motor 244, is used to trim the irregular ends of the weft wire. The cutter 240 may consist of a grinding wheel or any other suitable cutting material.

Although the preferred embodiment of the device has been described, it will be understood that within the purview of this invention various changes may be made in the form, details, proportion and arrangement of parts, the combination thereof and mode of operation, which generally stated consists in a device capable of carrying out the objects set forth, as disclosed and defined in the appended claims.

Having thus described my invention, I claim:

1. A weft wire crimping and feeding device for use in a loom having a beater having a reciprocatory movement, said weft wire crimping and feeding device including a pair of wire crimping wheels; means for rotating the wheels during the initial advance movement of the beater of the loom; means for arresting the movement of the crimping wheels before the beater reaches the advanced position; supporting means for loosely supporting the end of the weft wire as it advances across the warp wires during the feeding operation; and means for actuating the supporting means in response to movement of the beater.
2. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth, so that when the pinion engages the teeth of the arcuate rack member it is rotated, and means responding to the rotation of the pinion for actuating the crimping wheels; means for arresting the movement of the crimping wheels before the beater frame reaches the ad-

vanced position; supporting means for loosely supporting the end of the weft wire as it advances across the warp wires during the feeding operation; and means for actuating the supporting means in response to movement of the beater frame.

3. A weft wire crimping and feeding device for use in a loom having a beater frame having a reciprocatory movement, said weft wire crimping and feeding device including a pair of wire crimping wheels; means for rotating the wheels during the initial advance movement of the beater frame of the loom; means for arresting the movement of the crimping wheels before the beater reaches the advanced position; supporting means for loosely supporting the end of the weft wire as it advances across the warp wires during the feeding operation, actuating means for said supporting means, said actuating means including a rack fixedly mounted upon the loom; a pinion mounted upon the beater frame in the path of the rack so as to cause the pinion to be rotated when the pinion is in engagement with the rack; and means responding to the rotation of the pinion for actuating the supporting means.

4. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth so that when the pinion engages the teeth of the arcuate rack member it is rotated, and means responding to the rotation of the pinion for actuating the crimping wheels; means for arresting the movement of the crimping wheels before the beater frame reaches the advanced position; supporting means for loosely supporting the end of the weft wire as it advances across the warp wires during the feeding operation; a second rack; a second pinion; and means responding to the rotation of the second pinion for actuating the supporting means for loosely supporting the end of the weft wire as it advances across the warp wires.

5. A weft wire crimping and feeding device for use in a loom having a beater having a reciprocatory movement, said weft wire crimping and feeding device including a pair of wire crimping wheels; means for rotating the wheels during the initial advance movement of the beater of the loom; said means including a rocker arm; a pawl carried by the rocker arm for engaging one of the crimping wheels, means for arresting the movement of the crimping wheels before the beater reaches the advanced position, and supporting means for loosely supporting the end of the weft wire as it advances across the warp wires during the feeding operation.

6. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth so that when the pinion engages the teeth of the arcuate rack member it is rotated,

and means responding to the rotation of the pinion for actuating the crimping wheels; said last mentioned means including a rocker arm and a pawl mounted upon the rocker arm for engaging one of the crimping wheels to rotate the crimping wheels in one direction; means for arresting the movement of the crimping wheels before the beater frame reaches the advanced position; supporting means for loosely supporting the end of the weft wire as it advances across the warp wires during the feeding operation; and means for actuating the supporting means in response to movement of the beater.

7. A weft wire crimping and feeding device for use in a loom having a beater frame having a reciprocatory movement, said weft wire crimping and feeding device including a pair of wire crimping wheels; means for rotating the wheels during the initial advance movement of the beater frame of the loom; said means including a rocker arm, a pawl carried by the rocker arm for engaging one of the crimping wheels, means for arresting the movement of the crimping wheels before the beater reaches the advanced position; supporting means for loosely supporting the end of the weft wire as it advances across the warp wires during the feeding operation, actuating means for said supporting means, said actuating means including a rack fixedly mounted upon the loom; a pinion mounted upon the beater frame in the path of the rack having teeth so as to cause the pinion to be rotated when the pinion is in engagement with the teeth of the rack; and means responding to the rotation of the pinion for actuating the supporting means.

8. A weft wire crimping and feeding device for use in a loom having a beater frame having a reciprocatory movement, said weft wire crimping and feeding device including a pair of wire crimping wheels; means for rotating the wheels during the initial advance movement of the beater frame of the loom; said means including a rocker arm, a pawl carried by the rocker arm for engaging one of the crimping wheels, means for arresting the movement of the crimping wheels before the beater frame reaches the advanced position; supporting means for loosely supporting the end of the weft wire as it advances across the warp wires during the feeding operation, a rack having teeth, said rack being fixedly mounted upon the loom, a pinion mounted upon the beater frame in the path of the rack so as to cause the pinion to rotate when in engagement with the rack; and means responding to the rotation of the pinion for actuating the supporting means for loosely supporting the end of the weft wire as it advances across the warp wires.

9. A weft feeding device for use in a loom having a beater frame having a reciprocatory movement, said weft feeding device including a rocker arm; a pawl carried by the rocker arm, wire engaging feeding means actuated by the pawl, and means for oscillating the rocker arm; said last mentioned means responding to the reciprocatory movement of the beater frame for oscillating the rocker arm.

10. A weft wire feeding device for use in a loom having a beater frame having a reciprocatory movement, said weft feeding device including a rocker arm; a pawl carried by the rocker arm, wire engaging feeding means actuated by the pawl, means for oscillating the rocker arm, said last mentioned means responding to the reciprocatory movement of the beater frame for oscillating the rocker arm, and means for loosely sup-

porting the end of the weft wire as it is fed across the warp wires.

11. A weft wire feeding device for use in a loom having a beater frame having reciprocatory movement, said weft feeding device including actuating mechanism having an arcuate rack member fixedly mounted upon the loom, a pinion carried upon the beater frame and mounted in the path of the arcuate rack member having teeth so that when the pinion engages the teeth of the arcuate rack member it is rotated, means for engaging the weft wire for feeding same across the warp wires, and means responding to the rotation of the pinion for actuating the wire feeding means.

12. A weft wire feeding device for use in a loom having a beater frame having reciprocatory movement, said weft feeding device including actuating mechanism having an arcuate rack member fixedly mounted upon the loom, a pinion carried upon the beater frame and mounted in the path of the arcuate rack member having teeth so that when the pinion engages the teeth of the arcuate rack member it is rotated, means for engaging the weft wire for feeding same across the warp wires, means responding to the rotation of the pinion for actuating the wire feeding means, and means for arresting the movement of the pinion when the pinion disengages the rack teeth to thereby arrest the movement of the actuating mechanism.

13. A weft wire feeding device for use in a loom having a beater frame having reciprocatory movement, said weft feeding device including actuating mechanism having an arcuate rack member fixedly mounted upon the loom, a pinion carried upon the beater frame and mounted in the path of the arcuate rack member having teeth so that when the pinion engages the teeth of the arcuate rack member it is rotated, means for engaging the weft wire for feeding same across the warp wires, means responding to the rotation of the pinion for actuating the wire feeding means, and supporting means for loosely supporting the end of the weft wire as it is fed across the warp wires during the feeding operation.

14. A weft wire feeding device for use in a loom having a beater frame having reciprocatory movement, said weft feeding device including actuating mechanism having an arcuate rack member fixedly mounted upon the loom, a pinion carried upon the beater frame and mounted in the path of the arcuate rack member having teeth so that when the pinion engages the teeth of the arcuate rack member it is rotated, means for engaging the weft wire for feeding same across the warp wires, means responding to the rotation of the pinion for actuating the wire feeding means, supporting means for loosely supporting the end of the weft wire as it is fed across the warp wires during the feeding operation, and means for actuating the supporting means in response to the movement of the beater frame.

15. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth so that when the pinion engages the teeth of the arcuate rack member it is rotated,

5 a cam guide arranged in aligned relation with respect to the rack member, a cam mounted for rotation with the pinion, said cam engaging the cam guide when the pinion disengages the rack teeth, and means responding to the rotation of the pinion for actuating the crimping wheels; means for arresting the movement of the crimping wheels before the beater frame reaches the advanced position; supporting means for loosely supporting the end of the weft wire as it advances across the warp wires during the feeding operation; and means for actuating the supporting means in response to movement of the beater frame.

16. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth so that when the pinion engages the teeth of the arcuate rack member it is rotated, a cam guide arranged in aligned relation with respect to the rack member, a cam mounted for rotation with the pinion, said cam engaging the cam guide when the pinion disengages the rack teeth, and means responding to the rotation of the pinion for actuating the crimping wheels; means for arresting the movement of the crimping wheels before the beater frame reaches the advanced position; supporting means for loosely supporting the end of the weft wire as it advances across the warp wires during the feeding operation; a second rack having teeth, said second rack being fixedly attached to the loom; a second pinion mounted for rotation upon the beater frame, said second pinion being rotated when in engagement with the teeth of the second rack; and means responding to the rotation of the second pinion for actuating the supporting means for loosely supporting the end of the weft wire as it advances across the warp wires.

17. A weft wire crimping and feeding device for use in a loom having a beater frame having a reciprocatory movement, said weft wire crimping and feeding device including a pair of wire crimping wheels; mechanism for rotating the wheels during the initial advance movement of the beater frame of the loom, said mechanism including an arcuate rack member fixedly mounted upon the loom, a pinion carried upon the beater frame and mounted in the path of the arcuate rack member having teeth so that when the pinion engages the teeth of the arcuate rack member it is rotated, a cam guide arranged in aligned relation with respect to the rack member, a cam mounted for rotation with the pinion, said cam engaging the cam guide when the pinion disengages the rack teeth, and means responding to the rotation of the pinion for actuating the crimping wheels; means for arresting the movement of the crimping wheels before the beater frame reaches the advanced position; supporting means for loosely supporting the end of the weft wire as it advances across the warp wires during the feeding operation; a second rack having teeth, said second rack being fixedly attached to the loom; a second pinion mounted for rotation upon the beater frame, said second pinion being rotated when in engagement with the teeth of the second

rack; means responding to the rotation of the second pinion for actuating the supporting means for loosely supporting the end of the weft wire as it advances across the warp wires; a second cam guide arranged in aligned relation with respect to the second rack, and a second cam fixedly attached to the second pinion for engaging the second cam guide when the second pinion disengages the rack teeth for arresting the rotation thereof.

18. A mechanism for use with the manipulation of a weft wire used in a wire weaving loom having a beater frame having reciprocatory movement, said mechanism including rotatably mounted crimping members for engaging the weft wire, and means responsive only to the initial movement of the beater frame moving forward towards the fell for actuating said crimping members.

19. A mechanism for use in feeding a weft wire used in a wire weaving loom having a beater frame having reciprocatory movement, said mech-

anism including means for supporting the end of the weft wire, and means responsive only to the initial movement of the beater frame moving forward towards the fell for causing said first mentioned means to support the weft wire as it advances through the shed.
